UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR A SASH-LIFT.

Specification forming part of Design No. 5,990, dated July 16, 1872.

Specification describing a Design for a Sash-Lift, invented by OTTO F. FOGELSTRAND, of Kensington, in the county of Hartford and State of Connecticut.

The nature of my design is fully represented in the accompanying engraving, to which reference is made.

A represents the lift proper, and B its base-plate, of the contour shown in the drawing, and bordered by a raised ledge. *a a* represent screw-holes with a raised border in the form

of a star. Between said screw-holes is an ornamental figure in relief, as shown. The remaining space inside the border has a roughened surface.

I claim as my invention—

The design for a sash-lift, as shown in the accompanying drawing.

OTTO F. FOGELSTRAND.
